DESIGN FOR A TOY WAGON

Charles C. Blackmore, Oakwood, Ohio

Application January 19, 1935, Serial No. 54,929

Term of patent 7 years

To all whom it may concern:

Be it known that I, Charles C. Blackmore, a citizen of the United States, residing at Oakwood, in the county of Montgomery and State of Ohio, have invented a new, original and ornamental Design for a Toy Wagon, of which the following is a specification, reference being had to the accompanying drawing, forming a part hereof.

In the drawing Fig. 1 is a plan view of a toy wagon showing my new design; and Fig. 2 is a side elevation of the same.

The substantially rectangular outline in Fig. 1 indicates a recess in the body member.

I claim:

The ornamental design for a toy wagon as shown and described.

Dayton, Ohio, January 17th, 1935.

CHARLES C. BLACKMORE.
